TRAFFIC SIGNAL CIRCUIT

Application filed April 23, 1930. Serial No. 446,666.

The object of the invention is to provide a circuit arrangement for use in conjunction with the conventional crossing signals, whereby a siren may be incorporated and operated 5 at times or in periods of danger and all of the danger signals simultaneously operated and this without any modification of the conventional signal, insofar as wiring changes are necessary, except such additional leads 10 as are necessary to connect the additional parts employed in circuit.

With this object in view, the invention consists in a construction and arrangement of parts of which a preferred embodiment is 15 illustrated in the accompanying drawing which is a diagrammatic view of a conventional crossing signal with the apparatus included in the invention connected in circuit.

In the drawing the lamps R, A and G and 20 R', A' and G' are grouped according to the conventional fashion, the one group being observable from one direction and the other group from an angularly related direction. When the main or R light observable from 25 one direction is illuminated the corresponding G light observable from the other direction must be illuminated. Likewise, the R light and G' light must be simultaneously illuminated. Therefore, the positive terminals 30 of the R light and G' light are connected in on a lead 10, terminating at the binding post

11. Likewise, the positive terminals of the R' light and G light are connected in on a lead 12 carried to a binding post 14, the positive terminals of the A' and A lights being connected to the binding posts 15 and 16 by the leads 17 and 18. The negative terminals of the lights G and G' are connected, by 35 means of a conductor 19, with a binding post 20, as are also the negative terminals of the leads A and A'. The negative terminals of the leads R and R' are connected by means of a conductor 21 with a binding post 22. The above constitutes the circuit arrangement 40 of a conventional traffic signal.

In incorporating the invention, the siren or audible signal 23 is connected across the binding posts 22 and 20.

50 The rotary time switch 24 which is of conventional form has its collector ring 25 con-

nected by means of a conductor 26 with one terminal of a double-pole switch 27 and its segments 28, 29, 30 and 31 connected respectively to the bind-posts 11, 14, 15 and 16. The opposite pole of the switch 27 is connected by means of a conductor 32 with a binding post 22.

55 A triple-pole relay constitutes the element necessary to be included in circuit to carry out the invention and it has one of its arms 33 connected to the binding post 20 and the other arms 34 and 35 connected together and to a conductor 36 tapped in on the conductor 26. The arms 33, 34 and 35 are connected for synchronous movement and the arms 34 and 35 are adapted to be brought into engagement with the contacts 37 and 38 or separated therefrom, while the arm 33 is engaged with the contact 40 in one position of the relay and with the contact 39 in the other position. The 60 relay is actuated by means of a spring 41 to hold the arms in position where the arm 33 will be engaged with the contact 40 and separated from the contact 39, the arms 34 and 35 being correspondingly separated from 65 their respective contacts 37 and 38. A solenoid 42 constitutes an element of the relay to actuate the arms in opposition to the spring 41 and this solenoid is connected across the 70 conductors 36 and 32 and is controlled by a 75 manual switch 43.

The contact 39 is connected by means of a conductor 44 with the conductor 26 while the contact 40 is connected with the binding post 22 and the contacts 37 and 38 are connected to the binding posts 11 and 14 which may be done by tapping in on the conductors leading 80 from the segments 28 and 29 to said binding posts.

90 In the operation of the invention the switch 43 is normally open, being designed for closure by hand actuation. When the switch 27 is closed, however, the feed line is connected in on the signal and it operates 95 in the usual way when the time switch 24 rotates, current passing from one of the line conductors to one pole of the switch and thence over the conductor 26 to the collector ring 25 and thence to the different sectors of the time switch 24. If the sector 28 is in cir- 100

cuit closing position, the current flows to the binding post 11 and thence over the conductor 10 to the R light and the G' light and thence from the negative terminal of the former over the conductor 21 to the binding post 22 and from the negative terminal of the latter over the conductor 19 to the binding post 20, that portion passing to the binding post 20 then passing to the arm 33 of the relay and to the contact 40 and thence to the binding post 22, reuniting with the other division of the current and returning to the source over the conductor 32. When the time switch will have moved to a position that will render the segment 28 inoperative, the segments 30 and 31 will be rendered operative to connect the positive lead in on the binding posts 15 and 16, so that current will pass through the lamps A and A' and to the binding post 20 over the conductor 19, reaching the binding post 22 through the switch arm and contact 40 and thence returning to the source as when the R and G' lights were illuminated. Further angular movement of the time switch will render the segment 29 operative and current will then pass to the binding post 14 and thence to the positive terminal of the G light and corresponding terminal of the R' light, returning from the negative terminal of the latter to the binding post 22 and from the negative terminal of the former to the binding post 20, the arm 33, contact 40 and binding post 22, returning to the source over the conductor 32.

When it is desired to operate the audible signal or siren and render both the R and R' signals operative, the switch 43 is closed manually, which will result in energizing the solenoid 42 by which current will be supplied from the source over the conductor 36, through the solenoid, over the switch 43 and back over the conductor 32. The arms 33, 34 and 35 of the relay will then be moved to engage the contacts 39, 38 and 37, when the time switch 24 will be rendered inoperative, since current will then pass over the conductor 36 to the arms 34 and 35 and thence to the contacts 38 and 37 and to the binding posts 14 and 11 and over the conductors 12 and 10 to the positive terminals of the lights R' and R and thence from the negative terminals of the latter over the conductor 21 to the binding post 22 and thence back to the source over the conductor 32. But with the engagement of the arm 33 with the contact 39, the current leaving the positive pole of the switch will divide, part passing over the conductor 44 to the contact 39 and thence over the arm 33 to the binding post 20, making that positive, whereas in previous operations it was negative. This change in potential of the binding post 20 places the siren 23 across the supply line by reason of the binding posts 20 and 22 being then positive and negative. Thus, the siren will be subject

to an energizing current and will be put in operation. The lights A, A', G and G' will be rendered inoperative despite the rotation of the time switch 24 because their negative terminals are connected in on the binding post 20 which in the normal or spring retracted position of the relay is negative but which in the energized position of the relay is made positive and thus brought to the same potential as the positive terminals of the lamps A, A', G and G'.

Opening the switch 43 of course permits spring actuation of the relay and the restoration of the parts to normal position where the signals will operate in the conventional fashion.

The invention having been described, what is claimed as new and useful is:

1. In combination with a traffic signal having a plurality of sets of electrically energized clear and danger signals of which the positive terminals of the danger signals of one set are connected to the positive terminals of the clear signals of another set and the negative terminals of the clear signals and the negative terminals of the danger signals of different sets are respectively connected together, a time controlled switch interposed between the positive side of a supply source and said positive terminals to alternately energize the same, the negative terminals of the danger signals being connected in on the negative side of the supply source, a relay having a movable element connected to the negative terminals of the clear signals, and a pair of fixed contacts with either of which said movable element is engageable, one of the fixed contacts being connected in on the negative side of the supply source and the other being connected in on the positive side of the supply source and an audible signal connected between said movable element and the negative side of said supply source.

2. In combination with a traffic signal having a plurality of sets of electrically energized clear and danger signals of which the positive terminals of the danger signals of one set are connected to the positive terminals of the clear signals of another set and the negative terminals of the clear signals and the negative terminals of the danger signals of different sets are respectively connected together, a time controlled switch interposed between the positive side of a supply source and said positive terminals to alternately energize the same, the negative terminals of the danger signals being connected in on the negative side of the supply source, a relay having a movable element connected to the negative terminals of the clear signals, and a pair of fixed contacts with either of which said movable element is engageable, one of the fixed contacts being connected in on the negative side of the supply source and the other being connected in on the positive side of the supply source and the negative side of said supply source.

side of the supply source and an audible signal connected between said movable element and the negative side of said supply source, the relay including a plurality of additional movable members connected in on the positive side of the supply source, and fixed contacts respectively connected in between the time switch and the positive terminals of said signals, the last said contacts being engageable by the last said movable elements when the first said movable element is engaged with that contact connected in on the positive side of the supply source.

3. In combination with a traffic signal having a plurality of sets of electrically energized clear and danger signals of which the positive terminals of the danger signals of one set are connected to the positive terminals of the clear signals of another set and the negative terminals of the clear signals and the negative terminals of the danger signals of different sets are respectively connected together, a time controlled switch interposed between the positive side of a supply source and said positive terminals to alternately energize the same, the negative terminals of the danger signals being connected in on the negative side of the supply source, a relay having a movable element connected to the negative terminals of the clear signals, and a pair of fixed contacts with either of which said movable element is engageable, one of the fixed contacts being connected in on the negative side of the supply source and the other being connected in on the positive side of the supply source and an audible signal connected between said movable element and the negative side of said supply source, the relay including a plurality of additional movable members connected in on the positive side of the supply source, and fixed contacts respectively connected in between the time switch and the positive terminals of said signals, the last said contacts being engageable by the last said movable elements when the first said movable element is engaged with that contact connected in on the positive side of the supply source, the movable elements of the relay being spring actuated to normally engage the first said movable element with that contact connected in on the negative side of the supply source, and means to selectively control the relay to render it inactive or permit it to actuate the movable elements in opposition to the spring to engage all of them respectively with the other contacts.

In testimony whereof, I affix my signature.
DAVID HARLOW CALDERWOOD.
